UNITED STATES PATENT OFFICE.

HAROLD DUDLEY STROUD, OF CHICAGO, ILLINOIS, ASSIGNOR OF ONE-HALF
TO JAMES E. PLEW, OF SAME PLACE.

TELEPHONE-CALL RECORDER.

SPECIFICATION forming part of Letters Patent No. 860,826, dated October 30, 1900.

Application filed February 23, 1900. Serial No. 6,229. (No model.)

To all whom it may concern:

Be it known that I, HAROLD DUDLEY STROUD, of Chicago, Illinois, have invented certain new and useful Improvements in Telephone-Call Recorders, of which the following is a specification.

This invention relates to improvements in telephone-call recorders; and it has among its objects to provide a register or tallying mechanism whereby each call of a subscriber is automatically registered, to provide means whereby the subscriber may ascertain by inspection how many calls have been made, to provide means whereby the calls registered upon any one instrument may be automatically recorded at a given reading-station—as, for example, at "central"—to provide means whereby the register or tallying device may be automatically reset from said reading-station or from a given point on the system remote from the subscriber's station and at the same time a permanent record of the calls made since the last resetting of the instrument recorded, to provide an apparatus which may be readily adapted to most of the telephone systems now in common use, and in general to provide a simple, reliable, and inexpensive mechanism of the character referred to.

The invention consists in the matters hereinafter described, and more particularly pointed out in the appended claims, and will be readily understood from the following description, reference being had to the accompanying drawings, in which—

Figure 1 is a diagrammatic view of a telephone system equipped with my invention. Fig. 2 is a front plan view of the register mechanism, parts being broken away to expose certain features of mechanism contained within or located in rear of the parts broken away. Fig. 3 is a side elevation of the mechanism shown in Fig. 2.

Referring to said drawings, Fig. 1, *a* designates as a whole any usual switchboard located at "central;" *b*, the subscriber's instrument, connected with "central" by means of the conductors 1, 2, respectively; *c*, the printing mechanism conveniently located at "central" and by means of which a permanent record of the number of calls is printed; *d*,

the inspector's telephone set, and *e* the subscriber's-call recorder, located at the subscriber's station and comprising generally a tallying mechanism by means of which upon each call for a connection the subscriber operates a device whereby is caused to step forward a register-wheel 3, (a signaling device which notifies "central" that the call has been registered,) an escapement mechanism 4, the vibrations of the verge 5 of which are caused to make and break a circuit, which sends corresponding impulses to the printing instrument as the register mechanism is returned to zero, and an electromagnet 6, by means of which the register mechanism is released and allowed to return to zero under the influence of a spring or motor 7.

Describing the register mechanism more particularly, 3 designates a ratchet-wheel mounted rigidly upon a suitable shaft 8, journaled in bearings in the front and rear frame members 9, 10, respectively, (see Fig. 3,) of the register. At the front of the register is mounted a dial 11, provided with a circumferential series of gradations corresponding to the number of notches of the ratchet-wheel 3, in the present instance running from "0" to "100," and the main shaft 8 is extended at its forward end through the center of the dial 11 and provided with an indicator 12 arranged to sweep over the dial in the usual manner.

In order to step the ratchet-wheel forward a notch at a time each time the subscriber calls for a connection, a contact-lever 13 is pivotally mounted between its ends, as at 14, upon the front frame member 9, adjacent to said ratchet-wheel, one end of said lever being provided with a suitable handle or finger 15 hold, whereby it may be pulled downwardly, and the opposite end being provided with a push-pawl 15, which is normally out of engagement of the ratchet-wheel, but is brought into engagement therewith and caused to push it forward one notch each time the lever is pulled down far enough to close a circuit in a manner hereinafter described. Said push-pawl is pivotally mounted upon the end of the contact-lever, as indicated at 16, so as to permit it to follow the movement of the ratchet-wheel, and is held yieldably in posi-

tion to engage the ratchet-wheel properly by means of a stop 17 upon the lever 13, which engages one side of the pawl, and a spring 18, arranged at the opposite side of the pawl 5 and acting to hold the latter yieldingly in engagement with said stop except when carried away from the latter by its movement in following the ratchet-wheel.

19 20 designate two contact-terminals conveniently mounted in a block of insulating material 21 or otherwise suitably supported upon the frame-plate 9, adjacent to and below the lever 13, the uppermost member 19 being constructed of spring metal and having its free end arranged in position to be engaged and forced downwardly by a lug 22, of insulating material, mounted upon the contact-lever, while the lower member 20 is provided at its free end with an upturned portion 23, with which the free end of the spring-contact 19 is adapted to contact to close an electric circuit, as will be hereinafter described. The contact member 20 is made sufficiently rigid to serve as a stop to limit 25 the downward movement of the lever, so as to prevent the ratchet-wheel from being turned too far at a single movement, while the movement of the contact-lever in the opposite direction is limited, conveniently, by 30 means of a stop 24, located upon the frame-plate 9 above said lever. In order to return said ratchet-wheel to zero in the manner to be hereinafter described, a coiled watch-spring 7 is mounted upon the frame-plate 10, 35 concentrically with the ratchet-wheel 8, one end of said spring being engaged with the shaft, while its opposite end is made rigid with the frame-plate in such manner that the spring will be wound up or tensioned as the 40 ratchet-wheel is stepped forward. In order to hold the ratchet-wheel from backward movement as it is stepped forward, a detent 25 is mounted upon the frame-plate 9 in position to engage said ratchet-wheel and is 45 held yieldingly in contact with the latter by means of a spring 26.

Inasmuch as it is desirable to provide for recording a greater number of calls than could be conveniently indicated on the periphery of a single dial, a second recording-wheel is provided, so interconnected with the primary ratchet-wheel as to record the number of complete revolutions of the latter. Desirably and as shown herein the said secondary wheel consists of a spur-gear 26, mounted upon the inside of the dial-plate 11 and arranged to intermesh its periphery with a pinion 27, mounted rigidly upon the ratchet-wheel shaft 8, the number of teeth of said 55 pinion bearing a fixed relation to the number of teeth of the spur-gear—as, for example and as shown herein, as one to twelve—so that each time the ratchet-wheel performs one revolution the gear-wheel will be rotated one- 60 twelfth of a revolution. The stub-shaft upon which the spur-gear is mounted is extended out through the dial-plate and is provided

with an indicator 28, arranged to sweep over a smaller dial 29, divided into a number of divisions corresponding to the number of 7 revolutions of the driving-pinion required to impart a complete revolution to the spur-gear.

In order that the mechanism may become automatically locked against further movement whenever a number of calls have been made equal to the full number the apparatus is designed to register without resetting, the spur-gear or secondary register-wheel 26 is provided at its periphery with a stop-lug or 75 blank tooth 30, which when brought into engagement with the pinion 27 will positively lock the mechanism against further movement, thereby preventing the contact-lever from being drawn down far enough to close 80 the calling-circuit.

Means are provided for resetting the register to zero and at the same time recording at the reading-station a printed record of the number of calls, which means are constructed 90 and arranged as follows: 6 designates an electromagnet operated by a circuit controlled by the inspector at the reading-station and comprising the usual coil 31, conveniently mounted upon a bracket 32 upon the frame-plate 9 at a point vertically beneath the ratchet-wheel shaft, and an armature 33, 95 yieldingly supported above the coil 31 and normally held remote from the latter and in engagement with an electrical back contact 100 34 by means of a coiled spring 35. With the free or vibrating end of the armature 33 is connected a rod 36, by means of which the detent 25 is withdrawn from the ratchet-wheel when the armature is drawn downwardly by the energizing of the magnet, this end being accomplished, as shown in the mechanism in Figs. 2 and 3, by extending the upper end of said rod 36 upwardly to a point opposite the tail end of the detent 25, at which 105 point it is provided with a right-angled extension 37, which extends through a suitable vertical slot in the plate 9 and engages the upper side of said tail end of the detent in such position as to pull the latter downwardly, 110 and thus lift the detent out of engagement with the ratchet-wheel when the magnet is energized. In the diagrammatic view the construction is shown as slightly modified in order to render the diagram more clear, the 115 rod 36' being shown therein as connected with one arm of a bell-crank 38, the opposite arm of which is connected by means of a link 39 with a rocking cam 40, which serves to lift the detent out of engagement with the ratchet-wheel, when the cam is oscillated by the pulling down of the armature.

In order that the ratchet-wheel may be retarded in its unwinding movement and at the same time a circuit which controls the printing-register alternately opened and closed a 120 number of times equal to the number of ratchet-notches of the primary ratchet-wheel which pass by a given point in the resetting 125

of the mechanism, an escapement is provided, with the verge or vibrating member of which is connected a contact device arranged to open and close such controlling-circuit, said mechanism being desirably, and as herein shown, constructed and arranged as follows:

41 designates an escapement mounted loosely upon the main shaft 8 and provided at its periphery with a number of notches 42 equal to one-half the number of ratchet-notches upon the main ratchet-wheel 3.

45 designates a verge mounted upon an oscillatory shaft 43, arranged to extend between suitable bearings 44 and 45 upon the front 15 and rear frame-plates 9 and 10, respectively, said verge being supported in such relation to the escapement-wheel as to be oscillated positively by the unwinding movement of the latter in a familiar manner. With the upper portion of the verge is rigidly connected a contact-arm 46, which extends upwardly some distance and is then deflected rearwardly and arranged to extend at its rear end between a pair of contact-arms 47 47', mounted upon a suitable insulating-support 48 and in position to severally contact with the end of said contact-arm as the latter vibrates with the verge. In order to control the movement of the verge, the latter is provided with a 30 pendulum-arm 49, which is made rigid therewith and extends downwardly some distance within the frame and is provided at its lower end with an adjustable pendulum-weight 50. Springs 50', mounted at each side of the vibrating arm 46, serve to hold the latter from contact with the arms 47 and 47' except when vibrated positively by the verge.

In order that the escapement-wheel may remain stationary during the forward movement of the ratchet-wheel, so as not to vibrate the verge during such movement, it is mounted loosely on the main shaft, but is arranged to be driven positively in the reverse movement of said shaft by means of a ratchet-wheel 51, mounted rigidly upon the shaft adjacent to the escapement and engaged by a pawl 52, mounted upon the escapement-wheel and held yieldingly in contact with the ratchet by means of a spring 53.

50 A feature of the present invention consists in giving a signal to the operator at "central" each time a subscriber asks for and secures a connection, and means for giving such signal audibly is provided in the present instance by means of a "buzzer" or vibrator 54, which is of the usual well-known construction, its coils 55 and armature 56 being in circuit with one conductor 57 of the signaling-circuit, while its back-stop contact 58, 55 against which the armature or vibrating member 56 normally rests, is in circuit with the other conductor 59 of the signaling-circuit, so that whenever the contact-lever is pulled down to close the circuit between the contacts 19 and 20 the buzzer is thrown into action and an audible signal thus given to the operator at central.

The subscriber's telephone set *b* may be of any preferred and suitable construction, that illustrated in the diagram being of a usual type and comprising primary and secondary coils 60 61, respectively, transmitting and receiving phones 62 63, respectively, local battery 64, magneto 65, a subscriber's bell 66, and an automatic switch-lever 67, by means of which the circuit is automatically closed whenever the ear-phone is lifted from its hook 67', forming a part of said lever. A substantially similar telephone set is provided for the operator who takes the readings of the register, which, as hereinbefore mentioned, will preferably be located at "central," as indicated at *d*. At the reading-station will also be located a printing-recorder *c*, which will be operated by the alternate making and breaking of the circuit by the vibrator of the escapement as the register is returned to zero. In the diagram shown herein this printing instrument is represented as consisting of an ordinary tape-printer, which will automatically feed forward a strip of tape 68 and print or puncture a dot thereon each time the circuit is closed, this instrument being in common use for other purposes and of well-understood construction. Obviously any other suitable analogous tallying mechanism may be used for this purpose. In order to operate said printer *c* and also to operate the magnet 6 of the subscriber's register, a battery will be interposed in the circuit, as indicated at 69. A switch 70 is provided by which the circuit through the printer may be completed to "ground" and another switch 71, by means of which the inspector may place his telephone set in circuit at will, this latter switch being desirably so arranged that the operation of cutting the inspector's telephone into circuit will cut out the battery 69.

A pair of switches 72 73 are provided, desirably connected so as to move together, whereby the switchboard may be entirely cut off from the subscriber's circuit during such time as a reading is being taken.

Normally that part of the circuit which extends through the magnet 6 of the subscriber's register is open, so that said instrument is unaffected by the normal working of the other instruments on the line, and in order that this portion of the circuit may be closed when it is desired to take a reading a circuit-closing mechanism is provided, conveniently consisting of a push-button 74, seated in the dial-plate 11 and engaging at its inner end a spring contact-strip 75, which is adapted to be forced inwardly into contact with a second contact-strip or arm 76, also mounted upon the dial-plate, the said contact-strips being insulated from the plate 11 and respectively engaged with conductors 77 and 78. From the conductor 77, which extends through the coil of the magnet, a continuation 77' extends to ground.

In order that the magnet 6 may be kept energized and its armature held down until the

register has been returned completely to zero, even though the subscriber should release the contact-button 74 before the register has ceased its return movement, a branch conductor 78 is extended from the conductor 77, which passes through the magnet-coils 31 to a contact 78', with which the armature engages when the magnet is energized, so that when said magnet has once been energized 10 and the armature closed with the said contact 78' a circuit will be completed from main conductor 1 through the armature-lever, conductor 78, and the magnet to ground, thus holding the armature independently of that 15 portion of the circuit controlled by the push-button.

The operation of the apparatus and the several circuits brought into operation by the use thereof may be described as follows: Normally 20 the main circuit may be traced from the subscriber's telephone set through the main conductor 1 to the switchboard, through the latter and back by conductor 2 to the automatic switch-lever 67, at which point the circuit 25 will normally be broken, the said lever being held down by the ear-phone in contact with the back-stop 79 and away from the contacts 80 and 81. When the switch-lever is closed, this part of the main circuit will extend 30 through the ear-phone 63, thence through the secondary coil 61 to the armature 33 of the magnet 6, and through the latter to conductor 1, thus completing a circuit. From a point 82 on the conductor 2 a branch conductor 83 leads through the primary coil 60, thence through the local battery 64 to the transmitter 62, from whence one branch 84 leads to the contact 80 and a second conductor 57 leads to and through the buzzer 54. From 35 the back-stop 58 of the buzzer a conductor 59 extends to the contact 20, at which point the circuit is normally open. From the coöperating contact 19 a conductor 86 leads back to the transmitter. A conductor 87, extending 40 between the conductors 2 and 81', includes in its circuit the subscriber's bell 66, thus enabling the operator at "central" to call the subscriber at will.

The circuits and portions of circuits thus 50 far described are those which are only concerned in the normal working of the telephone, the operation of which may be briefly described as follows: When the subscriber wishes a connection, he first operates his magneto, which operates a "drop" upon the switchboard, thus notifying the operator at "central" which subscriber is calling, whereupon "central" connects her instrument with the subscriber, ascertains what connection is 55 wanted, and directs him to register his call by pulling down the lever of his register, it being understood that the subscriber places his ear-phone to his ear as soon as he has operated his magneto. As the subscriber pulls 60 down the contact-lever to give his signal to "central" the ratchet-wheel of the register 65 will be stepped forward one notch, thus re-

cording the call, and this same operation brings into action the buzzer 54, and thus signals "central" that the call has been registered, after which "central" makes the proper connection, it being understood that the resistance in the transmitter is sufficiently greater than that in the buzzer to insure such action.

Describing now the circuits by means of which the registering and printing mechanisms are controlled, it will be seen that from main conductor 1 a conductor 78 extends to the contact 76, which is normally open, that 75 from the coöperating strip 75 another conductor 77 leads to and through the coil of the magnet, and from the latter a conductor 77' extends to ground, so that when the contacts 75 and 76 are brought together a circuit is 80 completed from said main line conductor 1 through the magnet to ground. When the armature 33 is drawn down into bearing with the contact 78', a second circuit may then be 85 traced from the main conductor 1 through the armature 33 to said contact 78' to that 90 part of the conductor 77 which extends through said coils and thence by way of conductor 77' to ground, so that when said coils have once been energized and the armature 95 drawn down this latter circuit to ground will hold the armature closed. The opposite end of the circuit, located at the reading-station and which includes the battery 69, by means of which the magnet 6 is operated, comprises 100 a conductor 90, which extends from the switch 73 to and through the coil-switch 71, thence to battery 69 and to ground through conductor 91. The circuit, the impulses or alternate opening and closing of which caused 105 by the vibrator of the escapement operates the printing instrument, comprises at the subscriber's end a conductor 93, which extends from the main conductor 2 to the vibrator 46, and a return conductor 94, connected with 110 each of the contacts 47 and 47' and extending thence to and connecting with conductor 77, whence the circuit may be traced through conductor 78, the armature 33, and back by way of main conductor 1 to the printing instrument, thence through the battery and 115 main conductor 2 to the conductor 93 or the point of starting. Inasmuch as the drag of the detent 52 upon the ratchet-wheel 51 of the main shaft will tend to carry the escapement-wheel forwardly in the movement of the shaft I provide means for holding the vibrator 46 yieldably against being carried into contact with the arms 47 47' during such forward movement of the shaft. This is conveniently accomplished, as herein shown, by means of springs 50', mounted upon the front frame-plate 9 and arranged to embrace the 120 opposite sides of the vibrating arm 46.

The operation of restoring the register or 125 taking a reading is as follows: After the subscriber has registered a desired number of calls upon his register it may either be determined by the inspector's taking regular peri-

odical readings or by allowing the register to accumulate calls until it becomes automatically locked against further operation and the subscriber notifies "central" that he can no longer operate this register. The inspector will first cut out the main switchboard at "central" by shifting the switches 72 73 to throw the reading-station into circuit, after which he will shift the switch 71 to place his own telephone set in circuit with the subscriber's and will call up the latter by means of his calling-magneto. When the subscriber answers, the inspector will notify him that a reading is to be taken and request him to hang up his ear-phone and press the contact-button 74 to close the circuit through the magnet of his register. As soon as the inspector has thus notified the subscriber he will shift the switch 71 back into circuit with the battery 69 and will also close the switch 71, so that a circuit will be formed to ground through the conductor 91. After these operations have been performed the closing of the circuit by pressing the contact-button 74 will pull down the armature of the magnet 6, thus lifting the detent 25 free from the ratchet-wheel of the register, whereupon its spring will at once begin to return it to zero. The rotation of the main shaft 8 in this direction will impart a positive rotation of the escapement-wheel 41, which will vibrate the contact device 46, thus making and breaking the circuit each time the vibrator strikes either contact-arm 47 or 47'. These alternating makes and breaks of the circuit will operate the registering or printing instrument at the inspector's station, thus making an impression upon the recording-strip of the latter for each closing of the circuit, and inasmuch as the circuit will be closed and broken twice for each tooth of the escapement-wheel or once for each tooth of the ratchet-wheel the number of calls recorded by the printing instrument will obviously be equivalent to the number of calls which have been registered upon the register since the last reading. The subscriber's register will be arrested when it reaches its initial starting position by the contact of the stop-tooth 30 of the gear 26 of the pinion 27. It will be noted, as hereinbefore mentioned, that after the subscriber has once closed the circuit through the magnet of his register the said magnet will be kept energized, and the detent thereby held free from the ratchet-wheel by the circuit which extends from the main-line conductor 1 through the armature of the magnet and conductor 78 to ground. After the circuit has once been closed, so as to permit the register to begin its return movement, the remainder of the reading operation or the transfer of the calls from the subscriber's instrument to the inspector's recording instrument will be automatic and will only cease when the register is mechanically arrested. After the reading has been taken the inspector will simply restore the switches, placing

the subscriber's line in circuit with the switchboard as before. Obviously the subscriber may make a note of the reading of his register at the time he is notified that it is to be restored, thus enabling him to keep an exact record of the number of calls he should be charged with, while the inspector may take off the number of calls registered by the printing instrument at any time he sees fit and in any suitable manner, and it is to be noted in this connection that the operation of taking a reading or transferring the calls from the subscriber's register to the inspector's station will occupy but a very few moments' time, so that the interruption to the subscriber's line is reduced to a minimum. 75

While I have herein shown and described what I deem to be a preferred embodiment of my invention, yet it will be understood that the details thereof may be varied without departing from the spirit of the invention. For example, it will be obvious that my improved system could be readily adapted to a telephone system very materially different from that indicated herein, since the particular arrangement of the telephone system proper is only concerned incidentally in the use of my apparatus. It will be further obvious that both the subscriber's register and the register at the reading-station may be of modified construction so far as the broad invention is concerned. I do not therefore wish to be understood as limiting my invention to the details of construction or arrangement shown, except as they may be made the subject of specific claims. 90

I claim as my invention—

1. A telephone-call-recording system, comprising in combination with a subscriber's telephone set, a register instrument located at the subscriber's station, a mechanism for recording a call upon said register each time the subscriber asks for a connection, a second registering instrument located at a station remote from the subscriber's station, and electrical connections extending between said registering instruments whereby a series of accumulated calls recorded by the register at the subscriber's station may be automatically transferred and registered at the said station remote therefrom. 105

2. In combination with a subscriber's telephone set and the electrical connections leading from said set to the central station, a telephone-call-recorder system comprising a registering instrument located at the subscriber's station, mechanism for recording a call upon said register each time the subscriber asks for a connection, a second registering instrument located in electrical connection with the main lines of the telephone system, at a station remote from the subscriber's station, and means for transferring an accumulated series of registered calls comprising an electrical-impulse mechanism electrically connected with the main lines, and an actuating device 120 co-operating with the subscriber's register to 125

operate the impulse mechanism a number of times corresponding to, and determined by, the accumulated series of calls.

3. In combination with a subscriber's telephone set and the electrical connections leading from said set to the central station, a telephone-call-recorder system comprising a register instrument located at the subscriber's station, mechanism for recording a call upon said register each time the subscriber asks for a connection, a second registering instrument located in electrical connection with the main lines of the telephone system, at a station remote from the subscriber's station, adapted to be actuated synchronously with the subscriber's register to make a record of the calls registered by said latter instrument and means for cutting the central telephone-station out of circuit with the subscriber's line during the time the calls registered upon the subscriber's register are being transferred to the register of the station remote therefrom.

4. A telephone-call-recorder system, comprising in combination with a subscriber's telephone set, a registering instrument located at the subscriber's station, mechanism for recording a call upon said register each time the subscriber asks for a connection, a second registering instrument located at a reading-station remote from the subscriber's station, electrical connections extending between said registers and means whereby a plurality of calls registered at intervals apart upon the subscriber's register may be automatically transmitted to the register of the reading-station during the restoring of the subscriber's register to its initial starting position.

5. A telephone-call-recorder system comprising in combination with a subscriber's telephone set, a registering instrument located at the subscriber's station, mechanism for recording a call upon said register each time the subscriber asks for a connection, a second registering instrument located at a reading-station remote from the subscriber's station, electrical connections extending between said registers and means whereby a plurality of calls registered at intervals apart upon the subscriber's register may be automatically transmitted to the register of the reading-station during the restoring of the subscriber's register to its initial starting position, comprising an electrical make-and-break mechanism adapted to form an electrical impulse for each step of the register mechanism corresponding to a call thereon, in its restoring movement, substantially as described.

6. A telephone-call-recorder system comprising in combination with a subscriber's telephone set, a registering instrument located at the subscriber's station, mechanism for recording a call upon said register each time the subscriber asks for a connection, a second registering instrument located at a reading-station remote from the subscriber's

station, electrical connections extending between said registers and means whereby a plurality of calls registered at intervals apart upon the subscriber's register may be automatically transmitted to the register of the reading-station during the restoring of the subscriber's register to its initial starting position, comprising an electrical make-and-break mechanism adapted to form an electrical impulse for each step of the register mechanism corresponding to a call thereon in its restoring movement, said register at the reading-station comprising an electromagnet operated by the alternate opening and closing of the circuit and printing and paper-feeding mechanisms operated by said electromagnet whereby a mark is printed for each alternating opening and closing of the circuit, substantially as described.

7. A telephone call-recorder system, comprising in combination with a subscriber's telephone set, a registering instrument located at the subscriber's station, mechanism for recording a call upon said register each time the subscriber asks for a connection, and mechanism electrically connected with the main circuit of the subscriber's telephone, whereby the subscriber's register may be restored to its initial starting position from a station remote therefrom.

8. A telephone-call-recorder system, comprising in combination with a subscriber's telephone set a registering instrument located at the subscriber's station, comprising a register-wheel adapted to be stepped forward a step at a time each time a call is registered thereon, a motor acting upon said register-wheel and tending to normally return it to its initial recording position, a detent acting to normally prevent the restoration of the register-wheel to its initial position under the influence of the motor, electrical connections connecting said register with the subscriber's main telephone-circuit and means controllable through said circuit for releasing said detent to permit the register to return to its initial position, operable from a station remote from the subscriber's station, substantially as described.

9. A telephone-call-recorder system, comprising in combination with a subscriber's telephone set, a registering instrument located at the subscriber's station, comprising a register-wheel adapted to be stepped forward a step at a time each time a call is registered thereon, a motor acting upon said register-wheel and tending to normally return it to its initial recording position, a detent acting to normally prevent the restoration of the register-wheel to its initial position under the influence of the motor, electrical connections connecting said register with the subscriber's main telephone-circuit, means controllable through said circuit for releasing said detent to permit the register to return to its initial position, operable from a station remote from the subscriber's station and a normally open

contact device interposed in the electrical circuit extending between the main telephone-circuit and the register at the subscriber's station, adapted to be closed when it is desired to restore the register, substantially as described.

10. A telephone-call-recorder system, comprising in combination with a subscriber's telephone set a registering instrument located at the subscriber's station, comprising a register-wheel adapted to be stepped forward a step at a time each time a call is registered thereon, a motor acting upon said register-wheel and tending to normally return it to its initial recording position, a detent acting to normally prevent the restoration of the register-wheel to its initial position under the influence of the motor, electrical connections connecting said register with the subscriber's main telephone-circuit, means controllable through said circuit for releasing said detent to permit the register to return to its initial position, operable from a station remote from the subscriber's station, a normally open contact device interposed in the electrical circuit extending between the main telephone-circuit and the register at the subscriber's station, adapted to be closed when it is desired to restore the register, an electromagnet included 30 in that part of the circuit extending between the register and main telephone-circuit and a branch circuit normally open and adapted to be closed through said magnet when the latter is energized whereby the circuit from the station remote from the subscriber's station may be maintained and the restoring movement of the register controlled independently of the said contact device after the circuit has been once established, substantially as described.

11. In a register for telephone-calls and the like, the combination with an electric circuit and source of electricity of a registering member adapted to be moved forward step by step, means for returning said register member to its initial position, and a circuit-breaking device included in said electric circuit and operatively connected with the register member, said circuit-breaking device being constructed and operated to break the circuit a number of times proportionate to, or dependent upon, the number of steps the register member is stepped forward from its initial position.

12. In a register for telephone-calls and the like, the combination with an electric circuit and source of electricity of a register member adapted to be moved forward step by step, means for returning said register member to its initial position, and a circuit-breaking device included in said electric circuit and operatively connected with the register member, said circuit-breaking device being constructed and operated to break the circuit a number of times proportionate to, or dependent upon, the number of steps the register member is stepped forward from its ini-

tial position upon its return movement to said initial position.

13. In a register for telephone-calls and the like, the combination with an electric circuit and source of electricity, of a register member adapted to be moved forward step by step, a motor tending to return said register member to its initial position, a circuit-breaking device included in said electric circuit, operatively connected with the registering member and operating to break the circuit a number of times proportionate to, or dependent upon, the number of steps the registering member is stepped forward from its initial position and a retarding device acting upon said registering member to insure a gradual return movement.

14. In a register for telephone-calls and the like, the combination with an electric circuit and source of electricity, of a ratchet-wheel adapted to be moved forward step by step, a motor acting upon said ratchet-wheel and tending to return it to its initial position, an escapement mechanism operatively connected with said ratchet-wheel and a circuit-breaking device operatively connected with a vibrating part of the escapement, substantially as and for the purpose described.

15. In a register for telephone-calls and the like, the combination with an electric circuit and source of electricity of a registering ratchet-wheel adapted to be moved forward step by step, a motor acting upon said ratchet-wheel and tending to return it to its initial position, a detent arranged to normally prevent the return movement of the ratchet-wheel, and an electromagnet included in said electric circuit, and acting to withdraw the detent from the ratchet-wheel when energized.

16. In a register for telephone-calls and the like, the combination with an electric circuit and source of electricity of a registering ratchet-wheel adapted to be moved forward step by step, a motor acting upon said ratchet-wheel and tending to return it to its initial position, a detent arranged to normally prevent the return movement of the ratchet-wheel, and an electromagnet included in said electric circuit, acting to withdraw the detent from the ratchet-wheel when energized, an escapement-wheel operatively connected to move with the ratchet-wheel, a verge mounted to co-operate with said escapement-wheel, and a circuit-breaking device connected to and moving with said verge, said operative connections between the ratchet-wheel and escapement-wheel comprising a pawl-and-ratchet mechanism whereby the escapement-wheel is moved positively with the ratchet-wheel in the return movement of the latter, but is free to remain stationary during the forward movement of the ratchet-wheel.

17. In a register for telephone-calls and the like, the combination of a main shaft, a dial-plate arranged concentric therewith, an in-

18. A dial indicator upon the shaft arranged to sweep over said dial, a ratchet-wheel rigidly mounted upon the shaft, a manually-operable contact-lever provided with a push-pawl adapted to step said ratchet-wheel forward when the contact-lever is oscillated, a motor acting on said shaft and tending to return it to its initial position, a detent arranged to normally hold the ratchet-wheel against return movement, a fixed contact and a movable contact co-operating therewith adapted to be brought into bearing with the fixed contact by the movement of the lever to shift the ratchet-wheel and a signaling device included in said electric circuit and adapted to be operated by the closing of the said contacts, substantially as described.

19. In a register for telephone-calls and the like, the combination of a main shaft, a dial-plate arranged concentric therewith, an indicator upon the shaft arranged to sweep over said dial, a ratchet-wheel rigidly mounted upon the shaft, a manually-operable contact-lever provided with a push-pawl adapted to step said ratchet-wheel forward when the contact-lever is oscillated, a motor acting on said shaft and tending to return it to its initial position, a detent arranged to normally hold the ratchet-wheel against return movement, a fixed contact and a movable contact co-operating therewith, adapted to be brought into bearing with the fixed contact by the movement of the lever to shift the ratchet-wheel, a signaling device included in said electric circuit and adapted to be operated by the closing of the said contact, an escapement operatively connected to move with said ratchet-wheel during its return movement, a vibrating contact device operatively connected with said escapement and operating to break an electric circuit each time the escapement is oscillated and means for withdrawing and holding the detent free from the ratchet-wheel during the return movement of the latter.

20. A telephone-call-recording system comprising in combination with a subscriber's telephone set and the main telephone-circuit thereof, of a registering instrument located

at the subscriber's station, comprising a tallying mechanism adapted to be operated manually, a normally open branch circuit electrically connected with the main telephone-circuit, a contact device adapted to close said branch circuit each time the tallying mechanism is operated manually and a buzzer included in said branch circuit, adapted to be thrown into operation when said circuit is closed, substantially as described.

21. A telephone-call-recorder system comprising in combination with a subscriber's telephone set and the main telephone-circuit thereof, a manually-operable tallying mechanism located at the subscriber's station, a normally open branch electric circuit connected with the main telephone-circuit, a movable device adapted to be moved to close said branch circuit when the tallying mechanism is operated manually, a buzzer included in said branch circuit, a motor tending to return the tallying mechanism to its initial starting-point, an escapement arranged to control the return movement of the tallying mechanism, a contact make-and-break mechanism connected with the vibrating member of the escapement, a second branch circuit connected with the main line circuit and adapted to be alternately closed and opened by the escapement-operated contact device, a branch-circuit portion located at a reading-station remote from the subscriber's station and including an electrically-operated register, means for at will shifting the main telephone-circuit from the central switchboard to said branch-circuit portion located at the reading-station, an electromagnet connected with the subscriber's register and acting to release the tallying mechanism to permit it to return to its initial or starting position under the influence of the motor, and a branch circuit connected with the main telephone-circuit and extending through said electromagnet, whereby the latter may be operated from the reading-station, substantially as described.

HAROLD DUDLEY STROUD.
